Inventor:
Moses F. Carr,
by Ernest Booth Jameson Varney
Attest.

UNITED STATES PATENT OFFICE.

MOSES F. CARR, OF LEXINGTON, MASSACHUSETTS, ASSIGNOR TO CARR FASTENER COMPANY, OF CAMBRIDGE, MASSACHUSETTS, A CORPORATION OF MAINE.

FASTENER.

Application filed November 18, 1924. Serial No. 750,586.

This invention aims to provide an improved separable fastener.

In the drawings, which illustrate a preferred embodiment of my invention:—

Figure 1 is a front elevation of the fastener;

Fig. 2 is a section on the line 2—2 of Fig. 1; and

Fig. 3 includes a front, a side and a rear elevation of the preferred form of stud.

Referring to the drawings, I have shown a plurality of snap fastener members secured to their respective supports in such a manner as to permit two curtains to be secured to a rigid support, such as the body of an automobile or the like. In Fig. 2, I have shown the fastener members secured together so as to secure the curtains 1 and 2 to the body 3 of the automobile. The fastener parts, referred to above, include a stud 4 secured to the body 3 of the automobile, a socket 5 and a stud 6 secured to opposite sides of the curtain 2 and a socket 7 secured to the curtain 1.

The sockets 5 and 7 are similar in construction and each includes a casing 8 presenting a stud-receiving aperture 9 at its outer face and an aperture 10 at its inner face for purposes more fully hereinafter described.

The casing 8 contains a stud-engaging spring 11, which intersects the stud-receiving aperture 9, as illustrated.

The socket 7 is located at the inner face of the curtain 1 and is secured thereto by a tubular rivet 12, which is held by a cap member 13 located at the front face of the curtain 1. (Figs. 1 and 2). The rivet 12 passes through the curtain 1 and through the aperture 10 in the casing and is clenched against the inner face of the casing 8.

The preferred form of stud 6, which may be used wherever it is desired to rivet a stud to a metallic support, comprises a cap member having a laterally projecting head portion 14, a neck 15 of a diameter less than the head portion, a base portion 16 and a tubular rivet 17, herein shown as having a base flange 18 and a disc 19. (Fig. 3). All of these parts are secured together by crimping a portion of the base 16 of the cap member over the peripheries of the disc 19 and the base flange 18 of the tubular rivet 17. This stud 6 is secured to the front face of the curtain 2 and the socket 5 is secured to the inner

face of the curtain 2 by the rivet 17. In securing the stud 6 and socket 5 to the curtain 2, the rivet 17 is passed through the curtain 2, through the aperture 10 in the casing 8 and is clenched against the inner face of the casing, as illustrated in Fig. 2. The disc 19 back-supports the rivet 17 during the clenching operation, thereby preventing distortion of the rivet and insuring a tight grip on the curtain 2 between the stud 6 and the socket 5.

The stud 4 is secured to the body 3 by an attaching screw 20, and the construction of this stud is substantially as shown and more fully described in the United States Patent No. 1,433,783, issued October 31, 1922, to Carr Fastener Company, assignee of Moses F. Carr.

Both studs 4 and 6 are provided with a central depression 21, which, as illustrated in Fig. 2, receives the clenched portions of the rivets 12 and 17 when the studs and sockets are engaged. Thus I have provided a very simple and compact arrangement by which several curtains may be overlapped, secured together and secured to a single stud on the body of the automobile.

While I have shown and described a preferred form of one embodiment of my invention, it will be understood that changes involving omission, alteration, substitution and reversal of parts, and even changes in the mode of operation, may be made without departing from the scope of my invention, which is best defined in the following claims.

Claims:

1. A separable fastener stud comprising a cap part having at its outer end an annular rim providing a laterally projecting stud head, a neck portion below said head, and a base below said neck, an attaching part normally assembled with said cap part, said attaching part having a cap portion assembled with the base of said stud and a rivet portion of relatively smaller diameter than the neck of the stud, and means back supporting said rivet portion to prevent improper distortion thereof when the stud is being secured to a stud carrying medium.

2. A plural fastener installation including a stud and a socket secured to opposite sides of a single carrying medium, said stud presenting a depending rivet, and said socket presenting a casing having a rivet-receiving aperture therethrough, said rivet passed

through the carrying medium, through said aperture and clenched against the inner face of said socket.

3. A plural fastener installation comprising, in combination, a stud secured to a rigid support, a second stud and a socket secured to opposite sides of a single flexible support by a rivet extending from said second stud through the flexible support and through an aperture in said socket and clenched against the inner face of said socket and a second socket secured to a second flexible support by a rivet clenched against the inner face of the socket, both of said studs having de-pressed portions into which the clenched portions of said rivets extend when the studs and sockets are engaged.

4. A plural fastener including a stud and a socket secured to opposite sides of a flexible fabric, a rivet secured to said stud and back-supported by a plate interposed between the rivet and the base portion of the stud, said socket presenting a casing having an aperture therethrough, said rivet passed through the fabric and the aperture in said casing and supported by said plate while being clenched against the inner face of said casing.

5. A plural fastener including a socket and a stud secured to opposite sides of a single carrying fabric, said socket including a casing having a rivet-receiving aperture therethrough, said stud comprising a cap member having a head, a neck and a base, a rivet secured to said base, and supporting means for supporting said rivet when attaching said socket and said stud to the carrying fabric.

6. A plural fastener including a socket and a stud secured to opposite sides of a single carrying fabric, said socket including a casing having a rivet-receiving aperture

therethrough, said stud comprising a cap member having a head, a neck and a base, a hollow pressed rivet secured to said base, and supporting means for supporting said rivet when attaching said socket and said stud to the carrying fabric.

7. A plural fastener including a socket and a stud secured to opposite sides of a single carrying fabric, said socket including a casing having a rivet-receiving aperture therethrough, said stud comprising a cap member having a head, a neck and a base, a hollow pressed rivet secured to said base, and a reinforcing disc interposed between said base and said hollow rivet to support said rivet when attaching said stud and socket to the carrying fabric.

8. A hollow fastener stud including a cap member having a head, a neck and a base portion, a rivet secured to said base portion prior to attachment of the stud to a suitable carrying medium, means providing a space between the rivet and head of the stud, and rivet supporting means located between said rivet and the space between said head and said rivet to prevent said rivet being forced into said space when clenched to secure the stud to the carrying medium.

9. A fastener stud including a cap member having a head, a neck and a base portion, a tubular rivet having a base normally assembled with said cap, and an independent disc held between the base of the rivet and the cap member for back-supporting said rivet, said cap member, disc and rivet held in assembled relation by clenching a portion of the base of the cap member over the peripheries of the disc and the base of the rivet.

In testimony whereof, I have signed my name to this specification.

MOSES F. CARR.
